ROBERT W. BURROWS, OF PETALUMA, CALIFORNIA

FILLER PAD

Application filed March 19, 1929. Serial No. 348,182.

The present invention relates to improvements in filler pads for packing purposes generally and more particularly to a filler pad adapted for use in connection with the shipment of eggs or of fruits having particularly delicate, thin or easily bruised skins.

The invention has for its objects to provide a pad structure wherein a relatively cheap material is used in layer formation for filling purposes, and a more yieldable and softer material is used for a top or supporting surface, the layers being confined in an envelope. To provide a confining envelope having a face or surface of tissue or other soft material and a back or supporting surface of more rigid and of tougher material. Other objects are to provide a composite layer pad adapted for packing purposes generally, and which may be constructed cheaply and 20 which is designed for ready use where other pads are now employed.

With the above mentioned and other objects in view, the invention consists in the novel construction and combination of parts hereinafter described, illustrated in the accompanying drawing, and set forth in the claims hereto appended, it being understood that various changes in the form, proportion, size and minor details of construction within 30 the scope of the claims may be resorted to without departing from the spirit or sacrificing any of the advantages of the invention.

Referring to the drawing:—

Fig. 1 is a view in plan of the preferred embodiment of the invention with the tissue front wall or surface open to disclose the material therein.

Fig. 2 is a transverse sectional view illustrating the layers of material and the attachment of the tissue surface to the supporting back.

Fig. 3 is a view similar to Fig. 2 but taken at right angles thereto.

In the drawing, 1 indicates a back wall or supporting surface of cardboard of any suitable configuration and plan, and on its surface rests a layer 2 of excelsior or other equivalent material affording the main filler structure for the pad surface. The layer 2

may be of any desired thickness in accordance with the use to which the pad is to be put; and on the same rests a layer 3 of tissue material preferably in the form of strips of tissue paper. A sheet or cover 4 completes the envelope and is drawn over the layer of tissue material 3, and is secured as at 5 to the peripheral edges of the cardboard back 1.

It will be observed that this construction affords a yielding and at the same time relatively strong supporting back or wall surface for the pad, and presents a structure having an exceedingly soft and easily yielding supporting surface or face; this being made possible by the layer 3 of tissue material such as paper in strip formation, and the tissue paper front or surface which confines the excelsior filler and the tissue material 3 within an envelope and adapts the same for ready transporting or movement without the danger of spilling or the layers becoming separated.

If it is desirable, or found to be necessary, the layer of excelsior may be adhesively or otherwise secured to the face of the back 1, and the layer of tissue material may or may not, as the occasion demands, be adhesively secured to the surface of the excelsior layer.

I claim:—

1. A filler pad comprising a back member of flexible relatively heavy paper stock material, a layer of intertwined excelsior filler resting on the face thereof and forming a base, tissue strips arranged in layer formation and resting on said excelsior base and providing a yieldable filler surface, and a tissue covering extending over said tissue filler and secured to said back.

2. A composite filler pad comprising superimposed layers of intertwined excelsior and tissue strips with the excelsior forming a base for the tissue strips, a cardboard supporting back therefor, and a tissue sheet overlying said layers and secured at its edges to said back, said back and tissue sheet affording a confining envelope for the layers of excelsior and tissue strips.

3. A filler pad comprising an envelope having a front member and a back member of flexible stock, a layer of intertwined shred-

ded excelsior overlying and resting on said back member, a layer formed of intertwined elongated paper strips overlying and resting on said first mentioned layer, the flexible 5 front member for said pad being secured at its peripheral edge to said back member.

In testimony whereof I have signed my name to this specification.

ROBERT W. BURROWS.
